REFRIGERATOR CABINET

Filed Feb. 19, 1930

Inventor:
Henry S. Woodruff,
by *Charles E. Teller*
His Attorney.

UNITED STATES PATENT OFFICE

HENRY S. WOODRUFF, OF SCHENECTADY, NEW YORK, ASSIGNOR TO GENERAL ELECTRIC COMPANY, A CORPORATION OF NEW YORK

REFRIGERATOR CABINET

Application filed February 19, 1930. Serial No. 429,781.

My invention relates to refrigerator cabinets of the type having a refrigerating system associated therewith for cooling the cabinet.

5 In refrigerator cabinets of this kind, as heretofore constructed, the evaporators have generally been constructed so that the air in the cabinet flowing over the surfaces of the evaporator comes in contact with a small portion of the surface of the evaporator which has impaired their efficiency, and they have also been constructed so that they impeded the circulation of air in the cabinet.

10 The object of my invention is to provide a refrigerator cabinet having an evaporator therein of such form as to provide for a substantially unobstructed flow of air in the cabinet over the entire surface of the evaporator. I accomplish this by arranging a plurality of vertically arranged refrigerant containing plates in the cabinet in spaced relation so that air in the cabinet can flow freely over substantially the entire surface of the plates.

15 My invention will be more fully set forth in the following description referring to the accompanying drawing, and the features of novelty which characterize my invention will be pointed out with particularity in the 20 claims annexed to and forming a part of this specification.

Fig. 1 is a perspective view of a refrigerator having an evaporator therein constructed in accordance with my invention; Fig. 2 is a front elevation of the evaporator shown in Fig. 1; Fig. 3 is a side elevation in the evaporator, and Fig. 4 is a fragmentary longitudinal section of the header of the evaporator and one of the plates which are secured thereto.

As an example of one manner of carrying out my invention I have shown the same in connection with a refrigerator cabinet 10 having an evaporator 11 therein for cooling the cabinet which is suspended from a removable top 12. In this instance the refrigerating system associated with the evaporator 11 is of the compression type including a motor and compressor unit arranged in a casing 13 and which delivers compressed gas

25 to a condenser coil 14 supported on fins 15 secured to the case. The condenser coil 14 is connected at the lower end thereof to a float valve 16 which controls the flow of liquid refrigerant to the evaporator 11. The temperature of the evaporator is controlled by a thermostat 17 arranged in contact with the evaporator and connected to a control mechanism 18 for stopping and starting the motor which drives the compressor of the 30 refrigerating system. The general construction of this compression refrigerating machine is illustrated and described in Steenstrup Patent No. 1,736,635, November 19, 1929, which is assigned to the General Electric Company, assignee of the present invention.

35 The evaporators employed for cooling refrigerator cabinets of the type above described have ordinarily been arranged so that the air circulated in the cabinet came in contact with only a small portion of the surface of the evaporator and impeded the circulation of air in the cabinet. This is avoided in accordance with my invention by constructing the evaporator 11 of a plurality of flat plates 19 which are vertically arranged in the cabinet. These plates are spaced apart in substantially parallel relation and secured together at the upper edges thereof by a refrigerant containing header, 20 which is formed with arcuate openings 21 to afford communication between each of the refrigerant containing plates 19 and the header. The upper edges of the plates 19 are fitted over the openings 21 and are welded to the header as indicated at 22 in Fig. 4, so that the header serves to support the plates 19 in spaced relation to each other. The refrigerant level in the header 20 is maintained 40 slightly above the middle and approximately as indicated at 23, so that the refrigerant containing plates 19 are entirely filled with liquid refrigerant. The evaporator 11 is supported by lugs 11' which are welded to the plates 19 and bolted to the top 12.

45 The circulation of the air in the cabinet over the surfaces of the plates 19 vaporizes the liquid refrigerant and, unless this vaporized refrigerant is removed from the inner

surface of the plates, it interferes with the conduction of heat from the walls of the plates to the liquid refrigerant. In order to remove the vaporized refrigerant from the plates, I provide a plurality of passages forming closed paths in the plates for the circulation of liquid refrigerant which carries the vaporized refrigerant to the header 20 as rapidly as it is formed in the passages. 10 This is particularly important in an evaporator having vertically arranged plates, because in a construction of this kind it is quite difficult to obtain a satisfactory flow of vaporized refrigerant to the header from the 15 portions of the refrigerant containing plates remote from the header. The closed paths for the circulation of liquid refrigerant in the plates 19 may be formed in any desired manner, but in the present construction I 20 form them by making the plates 19 of two parts which are stamped out of flat metal sheets so that a plurality of corrugations are formed terminating inside of the outer edges of the sheets, the portions 24 of the corrugations 25 extending outwardly from the plane of the edge of the sheets to form passages, and the portions 25 of the corrugations being formed in the plane of the edge of the sheets. The portions of the sheets between the ends 30 of the corrugations and the edge of the sheets are depressed at 19' from the plane of the edges of the sheets to the same extent as the portions 24 of the corrugations. Two sheets 35 thereof and throughout the length of the portion 25 of the corrugations. The pairs of sheets which are welded together in this way to constitute the plates 19 form a horizontal passage 26 across the upper portion 40 thereof and a plurality of downwardly extending passages 27 communicating therewith between the portions 24 of the corrugations, and open at the lower ends thereof into a horizontal passage 28 extending across the 45 lower portions of the plates. By this construction the air circulating over the surfaces of the evaporator in the cabinet vaporize the refrigerant in the plates 19 and cause the liquid refrigerant to circulate very rapidly 50 from the lower edge to the upper edge of the plates in a plurality of closed paths as indicated by the arrows in Fig. 2. In this way the vaporized refrigerant is carried by the liquid refrigerant from the inner surfaces of 55 the plates 19 to the horizontal passage 26, thence to the header 20 of the evaporator as rapidly as it is formed, and the vaporized refrigerant does not, therefore, interfere with the transfer of heat from the walls of the 60 evaporator to the liquid refrigerant.

During the operation of the refrigerating system which is associated with the cabinet 10, liquid refrigerant is supplied through the float valve 16 to the header 20 of the evaporator through the pipe 29 and vaporized re-

frigerant is withdrawn from the header 20 by the compressor of the refrigerating machine through the pipe 30 which extends into the evaporator above the level 23 of liquid refrigerant. 70

Modifications of the form of my invention which I have illustrated and described will occur to those skilled in the art, so that I do not desire my invention to be limited to the particular construction set forth, and I intend in the appended claims to cover all modifications which do not depart from the spirit and scope of my invention. 75

What I claim as new and desire to secure by Letters Patent of the United States is: 80

1. A refrigerator cabinet having a refrigerating system provided with an evaporator arranged in said cabinet, said evaporator including a plurality of vertically arranged refrigerant containing plates, said plates being spaced apart to provide an unobstructed flow of air between them and over the entire surface of said plates, each of said plates having passages therein extending across the upper and lower portions thereof and connected by vertical passages, and a header secured directly to the upper portions of said plates for securing them together and communicating with the passages in the upper portions thereof. 90

2. An evaporator for refrigerating systems including a plurality of flat refrigerant containing plates spaced apart to provide for an unobstructed flow of air between them over the entire surface of said plates, said plates being vertically arranged and having passages therein arranged to provide for the circulation of liquid refrigerant in a plurality of closed paths, and a refrigerant header secured directly to the upper portion of said plates communicating directly with said passages. 1

3. An evaporator for refrigerating systems including a plurality of flat refrigerant containing plates spaced apart to provide for an unobstructed flow of air between them over the entire surface of said plates, said plates being vertically arranged and having passages therein extending across the upper and lower portions thereof and connected by vertical passages, and means including a header secured directly to the upper edges of said plates and communicating with said passages for supplying refrigerant thereto and for securing said plates together. 1

4. An evaporator for refrigerating systems including a plurality of vertically arranged substantially parallel flat plates spaced apart to provide for an unobstructed flow of air between them over the entire surface of said plates, said plates having a passage across the upper portions thereof and other passages arranged to form a plurality of closed paths for the circulation of liquid refrigerant, and means including a header se-

cured directly to the upper edges of said plates and communicating with the passages in the upper portions thereof for supplying refrigerant to said plates, said header extending transversely of said plates.

In witness whereof, I have hereunto set my hand this 18th day of February, 1930.

HENRY S. WOODRUFF.
